UNITED STATES PATENT OFFICE.

ROBERT G. OSBORN, OF DAYTON, OHIO, ASSIGNOR TO DELCO-LIGHT COMPANY, OF DAYTON, OHIO, A CORPORATION OF DELAWARE.

REFRIGERATING APPARATUS.

Application filed October 3, 1923. Serial No. 666,243.

To all whom it may concern:

Be it known that I, ROBERT G. OSBORN, a citizen of the United States of America, residing at Dayton, county of Montgomery, 5 and State of Ohio, have invented certain new and useful Improvements in Refrigerating Apparatus, of which the following is a full, clear, and exact description.

The present invention relates to refrigerating apparatus and more particularly to the control of the liquid refrigerant passing into the evaporator.

One of the objects of the present invention is to control the passage of fluid in a 15 duct connected with a vessel, such as an evaporator, by mechanism adjustable from the exterior of said vessel and by mechanism including a valve removable from the vessel without disassembling the same.

20 Further objects and advantages of the present invention will be apparent from the following description, reference being had to the accompanying drawing, wherein a preferred form of embodiment of the present invention is clearly shown.

In the drawing:

Fig. 1 is a fragmentary cross sectional view in a vertical plane of an evaporator provided with the present invention, and 30 Fig. 2 is a view showing the evaporator connected with a refrigerating system.

Referring to the drawing, 20 is a compressor driven by an electric motor 22. The gas to be compressed enters through pipe 23 35 and is expelled through a pipe 24. The compressed refrigerant passes through the condenser 25 where it is cooled in any suitable manner and liquefied and from thence it passes into the evaporator 26. The gaseous 40 contents of the evaporator is drawn into the compressor 20 through pipe 23.

Referring more particularly to Fig. 1 the evaporator 26 comprises a header 30 having an end cover 31 attached to the header by 45 bolts 32. The end cover 31 is provided with an inwardly extending hollow boss 33 providing a duct, the end of which is provided with a relatively small opening 34 and a valve seat 35. A valve 36 cooperates with 50 the valve seat 35 and has a stem 37 extending through the opening 34. The boss 33 is internally threaded to receive a nut 38 having a screw driver slot 39 and a passage 40. A spring 42 is interposed between the back 55 of valve 36 and the nut 38 and normally

maintains the valve 36 upon the seat 35. The hollow portion of the boss 33 extends through the opposite end of the end cover 31 and is enlarged and screw threaded to receive the coupling 43 connected with the 60 pipe 24. Cover 31 is also provided with a hole 44 which receives a pipe 45 and is connected in any suitable manner to the coupling 46 which in turn is connected to the pipe 23 and said pipe 45, the hole 44 forming an outlet from the header 30.

Float lever 48 is pivoted at 49 to the boss 33 and carries the float 50. Lever 48 has a downwardly projecting arm 51 which is adapted to engage the stem 37 of the valve 70 36 to move the valve away from the seat 35 whereby liquid refrigerant will pass through opening 34 into the header. After the level of the liquid refrigerant within the header 30 rises to a certain height the arm 51 of 75 lever 48 will move out of engagement with the finger 37 permitting the valve 36 to be returned to its seat 35 through the aid of spring 42.

It will be apparent from the foregoing 80 description that certain advantages are present in the present invention. The height of the liquid level within the header can be controlled from the exterior of the header. By adjusting the nut 38 the spring tension 85 on the valve 36 can be controlled whereby more or less force is necessary for opening or closing the valve, therefore the force necessary for opening the valve can be adjusted. 90

The present structure provides a valve which is readily removable from the exterior of the header without dismantling 95 said header whereby the valve and valve seat may be readily repaired when not operating correctly. By merely disconnecting the coupling 43, the adjusting nut 38, the spring 42, and valve 36 can be removed.

While the form of mechanism herein 100 shown and described constitutes a preferred embodiment of one form of invention, it is to be understood that other forms might be adopted, and various changes and alterations made in the shape, size and proportion of the elements therein without departing 105 from the spirit and scope of the invention.

What is claimed is as follows:

In refrigerating apparatus of the class described, a vessel adapted to contain a liquefied refrigerating material, a boss car- 110

ried by a wall of said vessel and extending thereinto, and having a liquid supply duct extending therethrough and through which liquid is supplied to the interior of said vessel, said duct being screw threaded at its outer end, and having a valve seat at its inner end, a valve arranged within said duct and adapted to cooperate with said valve seat, a spring located within said duct and 10 one end of which acts upon said valve, a threaded abutment arranged within said duct and in engagement with the threaded portion

thereof, and against which the other end of said spring abuts, and a float member located within said vessel and supported from the inner end of said boss and cooperating with 15 said valve to control the same, said duct being internally threaded exteriorly to the adjustable abutment aforesaid to permit a liquid supply conduit to be detachably connected therewith.

In testimony whereof I hereto affix my signature.

ROBERT G. OSBORN.
